Inventor:

H. E. Hawk

UNITED STATES PATENT OFFICE.

HALE E. HAWK, OF KANSAS CITY, MISSOURI.

CAR-COUPLING.

SPECIFICATION forming part of Letters Patent No. 280,743, dated July 3, 1883.

Application filed January 15, 1883. (No model.)

To all whom it may concern:

Be it known that I, HALE E. HAWK, a citizen of the United States, residing at Kansas City, in the county of Jackson and State of Missouri, have invented certain new and useful Improvements in Car-Couplings; and I do hereby declare that the following is a full, clear, and exact description of the invention, which will enable others skilled in the art to 10 to which it appertains to make and use the same, reference being had to the accompanying drawings, forming part of this specification.

My invention has for its object a novel combination and arrangement of devices for adaptation to the draw-head and shackle of a car without necessitating a change in the construction of the latter, and which will act to elevate the bolt, self-couple, and also form a safety-coupling when either shackle or bolt 20 is broken and prevent the separation of any part of the train; and it consists, first, in the mechanism arranged upon the draw-head of a car, whereby the bolt is raised to admit the entrance and withdrawal of the shackle; second, the mechanism upon the draw-head which 25 operates to elevate the bolt and also constitutes part of the safety-coupling; third, in a compound shackle and the devices for self-coupling and retaining the same from retraction either above or below the draw-head.

In the drawings, Figure 1 is a side elevation of the draw-head and safety coupling mechanism. Fig. 2 is a front view of the same. Fig. 3 is a vertical sectional view of Fig. 1, and 35 showing also my improved shackle.

A represents a draw-head of a car; B, a coupling-bolt, arranged in the draw-head in the common and well-known manner.

C is a lifting-bar arranged transversely 40 above the draw-head, of sufficient width to pass in line with the bolt B, and is perforated midway, as at i, to receive said bolt and raise the same from its seat in the draw-head. Lifting-bar C is made to extend a sufficient distance 45 from the sides of the draw-head to receive the vertical bolts D D, which are attached to the lifting-bar C, and held in place by the nut b above the bar and washer a below said bar.

G is a guide-box arranged transversely 50 beneath the draw-head, and attached thereto by an angle-iron, K, each end of said angle-iron

passing through the upper plate of the guide-box G, and securing the respective parts by nuts d d to the draw-head.

I is a supporting-bar attached to the guide-box, and also to the draw-head, giving increased strength to the same for resisting the shock in coupling.

L is a cross-bar attached to lifting-bolts D D. M is a shackle, and O a self-adjusting arm 60 on the latter, having inclines n and r and catch q, and attached to shackle M by the vertical bar N.

In the construction of my coupling devices I arrange in a transverse relation to and above 65 the draw-head, in line with the coupling-bolt B, a bar, C, of sufficient length to project over the sides of the draw-head and perforate said bar at each end to receive the vertical lifting-levers D D, and centrally to receive the coupling-bolt B.

Beneath the draw-head, and attached transversely thereto by an angle-iron, K, which passes around said draw-head, is a guide-box, G, of a sufficient length to project beyond the 75 sides of the draw-head, and is perforated above and below to receive the vertical lifting-bolts D D. The bolts D D, and also the coupling-bolt B, are arranged to move connectedly with the bar C, the nut b and washer a securing the 80 bolts D D to the bar C.

To each of the vertical lifting-levers D D, and in a transverse relation to and beneath the draw-head, I attach a cross-bar, L, which bar may be removably attached to the lifting-levers, if desired.

To the common shackle M, by means of a vertical bar, N, I attach a self-adjusting arm, O, parallel with the shackle, and secured thereto at the points s and t. The self-adjusting arm 90 O is further constructed with raised or beveled ends r, incline n, and catch q, which act, respectively, to raise the shackle, elevate the coupling device, and serve as a safety-coupling in the event an injury to or a disability 95 in the bolt or shackle to withstand the strain applied thereto should occur.

In combining my adjustable devices with the draw-head I obtain a safety-coupling which is peculiarly adapted to receive and be operated by the novel form of shackle. The self-adjusting arm O and the shackle M constitute 100

a compound shackle which is applicable to other devices for self-coupling, as shown in an accompanying application.

In operating my devices, and in introducing the shackle provided with my self-adjusting arm, the latter comes first in contact with the lower portion, *k*, of the guide-box *G*, the beveled end *r* upon the same having such an inclination that in all the variable heights of draw-bars it will impinge upon the inner portion, *k*, of said guide-box and throw said arm upward. The opening *c* in the draw-head and the portion *k* of the guide-box, when said devices are applied, correspond in vertical measurement with that given from the upper surface of the shackle and the lower parallel surface of the self-adjusting-arm, and will permit the shackle to pass into the draw-head and the self-adjusting arm to ride inwardly upon the portion *k* of the guide-box arranged below. Upon the approach of the shackle and self-adjusting arm *O* to the coupling devices for a safety-coupling, the incline *n* upon the upper portion of the arm and the beveled end *r* below the same, when brought in contact with the cross-bar *L*, wedge and throw said bar upward, and elevate thereby the coupling-bolt. The incline *n* upon the self-adjusting arm *O* is in oblique measurement equal to that required to elevate the bolt and admit the shackle within the draw-head in position for coupling, so that when the cross-bar *L* drops into catch *g* in rear of said incline the coupling-bolt falls at the same moment to couple the shackle. To withdraw the shackle, the bolt is first raised by suitable devices attached to the top and sides of a car. In the application of my device to a freight or platform car the release of the bolt may be effected by slightly extending bar *C* to receive a device applicable to the purpose.

The self-adjusting arm I have preferred to arrange below the shackle for convenience in operating the same; but said devices may be arranged horizontally with the shackle and the coupling effected in the same plane with the shackle.

Having fully described my invention, what

I claim as new, and desire to secure by Letters Patent, is—

1. In combination with the draw-head of a car, a transversely-arranged perforated guide-box attached outwardly to and beneath said draw-head, and extending a suitable distance beyond the sides of the same to receive the lifting-bolts, which are attached to the coupling-bolt, and relatively below said draw-head, to receive a suitable inclined device attached to and elevating the shackle to meet the opening in the draw-head, substantially as shown and described. 50
2. In combination with the draw-head of a car provided exteriorly with a suitable guide-box arranged beneath and extending beyond the opposite sides of said draw-head, and oppositely-arranged lifting-bolts in said guide-box, which are connected with the coupling-bolt, a transversely-arranged rod or bar connected with said lifting-bolts, and arranged within said guide-box and at a relative distance below said draw-head to admit a suitably-inclined device attached to the shackle passing between said bar and guide-box, and thereby elevating the coupling-bolt, substantially as specified. 65
3. A safety-coupling for a car, consisting of an arm attached to and beneath the shackle by a suitable bar and provided with oppositely-inclined ends, and a catch arranged upon said bar and in rear of said inclines, for the purpose set forth. 70
4. In combination with the draw-head of a car, having a suitable guide-box arranged upon and beneath the same, and a transversely-arranged bar within said guide-box, attached to the lifting devices, which are connected with the coupling-bolt, a safety coupling device consisting of an arm attached to and beneath the shackle by a suitable bar and provided with oppositely-inclined ends, and a catch arranged upon said bar, for the purpose specified. 80 85 90 95
